CLAIM

The ornamental design for a camera harness, as shown and described.

DESCRIPTION

FIG. 1 is a front, top, and left side perspective view of a camera harness;

FIG. 2 is a rear, top, and right side perspective view thereof; FIG. 3 is a front, bottom, and left side perspective view thereof;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a top plan view thereof; and,

FIG. 9 is a bottom plan view thereof.

(Continued)

The broken lines in the drawings showing portions of the camera harness are included for the purpose of illustrating environmental structure and form no part of the claimed design.

1 Claim, 9 Drawing Sheets
